Attorney

UNITED STATES PATENT OFFICE.

LOUIS GREILICH, OF DAYTON, KENTUCKY, ASSIGNOR OF ONE-HALF TO JOHN J. BAUER,
OF CINCINNATI, OHIO.

ARCH-SUPPORT.

1,200,187.

Specification of Letters Patent.

Patented Oct. 3, 1916.

Application filed October 5, 1915. Serial No. 54,267.

To all whom it may concern:

Be it known that I, LOUIS GREILICH, a citizen of the United States, and a resident of Dayton, in the county of Campbell and State of Kentucky, have invented new and useful Improvements in Arch-Supports, of which the following is a full, clear, and exact description, reference being had to the accompanying drawings, which form a part of this specification.

My invention relates to arch supports, and particularly to such as are built in during the construction of a shoe.

The object of my invention is to provide an arch support which may be built in during the construction of a shoe, so that the shoe is provided with a suitable arch support continuously available through the life of the shoe. The benefits to be derived from such an arch support are simplicity of construction and continuous availability, whereby the wearer is at all times in receipt of the benefits to be derived from arch supports.

In the drawings: Figure 1 is a bottom view of the insole of a shoe provided with my new arch supports. Fig. 2 is a side elevation of the same. Fig. 3 is an elevation of a shoe provided with said arch supports.

The numeral 1 indicates a shoe of any ordinary construction, 2 is the insole of said shoe and 3 indicates the counter thereof.

My invention consists in stitching to the shank of the insole 2, pieces or plates of leather or other suitable material 4 and 5, the said plates being shaped over the last upon which the shoe is to be constructed to fit against the sides of the arch of the wearer. The stitching for the attachment

of said plates is clearly indicated in Fig. 1 of the drawings wherein it will be noted that the plates 4 and 5 are secured to the under-side of the insole against the projection 6 of said insole on respective sides of the shank. When the insole thus provided with the supports 4 and 5 is inserted in the shoe 1 in the usual manner, it will be noted that the supports overlap as shown at 7 in Fig. 3 the counter of the shoe and rests inside said counter. The counter therefore supplements the supports and gives to the same additional rigidity and supporting efficiency.

It is apparent of course that the plates 4 and 5 may be made of any suitable material the requirements being a suitable stiffness, together with a sufficient flexibility or elasticity to adapt themselves to the arch of the wearer. I prefer, however, to make the same of a good quality of leather which combines the requirements and is well adapted to give efficient service for the purpose designed.

Having thus described my invention, what I claim is new and desire to secure by Letters Patent is:

In a shoe provided with a counter and a ribbed insole, a built-in arch support, said support comprising plates secured to the sides of the insole of said shoe and abutting against the ribs on the underside thereof, said plates overlapping the counter of said shoe and conforming to the arch of a foot.

LOUIS GREILICH.
